UNITED STATES PATENT OFFICE.

EDUARD H. TEMPERLI, OF EL CERRITO, CALIFORNIA.

COMBINATION SQUARE.

Application filed May 29, 1922. Serial No. 564,447.

To all whom it may concern:

Be it known that I, EDUARD H. TEMPERLI, a citizen of the United States, and a resident of El Cerrito, county of Contra Costa, and State of California, have invented a new and useful Combination Square, of which the following is a specification.

My invention relates to a combination square such as is particularly used by mechanics.

An object of the invention is to provide a combination square of extremely simple construction which may be used for a great many purposes in laying out work.

Another object of the invention is to provide a combination square which affords extreme accuracy.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims.

Referring to said drawings:

Figure 1 is a side elevation of the device in position for use as a bevel protractor.

Figure 2 is a plan view of the square.

Figure 3 is an end view of the frame viewed from the right of Figure 1.

Figure 4 is an end view of the square viewed from the left of Figure 1.

Figure 5 is a vertical section of the square taken on the line 5—5 of Figure 1, except that the scale is swung to horizontal position.

Figure 6 is a sectional view of one of the parts of the scale adjusting member, the plane of the section being indicated by the line 6—6 of Figure 10.

Figures 7, 8, 9, 10, 11 and 12 are side views of the various parts of the scale adjusting member.

Figure 13 is a perspective view of the device in position as a square or depth gauge.

Figure 14 is a vertical section of the frame, the parts in dotted lines indicating the method of scribing the center line on a taper shaft. The plane of the section is taken on

the line 14—14 of Figure 1, the blade however having been shifted so as to be included in a section.

The combination square in the present embodiment of the invention comprises a rectangular frame 2 preferably made of a single casting. Lying substantially midway between the broadsides 3 and 4 of the frame and extending longitudinally thereof is a slot 6 in which a blade or scale 7 is adapted to slidably fit. Formed on one of the longer sides 8 of the frame is V-shaped depression 9 which extends from one end of the frame to the other. The depression 9 communicates with the slot 6, the apex 12 of the depression being disposed at the juncture of the side 13 of the depression and the side 14 of the slot, as clearly shown in Figure 5. This construction is of considerable advantage since the mechanic may readily ascertain the center of a shaft and the longitudinal center line thereof without the use of the usual V-blocks and surface gauge. By holding the blade in the slot so that one of the longer edges of the blade lies flat against the angular face 17 of the slot and placing the shaft in the V-depression and against said edge of the blade as shown in Figure 4, the center of the shaft may be readily marked.

If it is desired to mark the center line of the shaft on the surface thereof, the scribe 18 or other suitable marking tool may be run along the shaft against the side 19 of the frame as indicated in the figure last mentioned. In order that the V-slot may be used for marking a center line on taper shafts, a longitudinal extending portion 20 of the side 13 of the depression is cut away at the apex, so that when a taper shaft is placed in the depression and the longer edge of the blade held flat thereagainst as shown in Figure 14, the point of a scribe may be inserted into the depression from the broad-side 3 of the frame and then run along the shaft at the side of the blade intersecting the apex of the depression.

Means are provided for enabling the blade to be held in various positions and for indicating the angularity of the blade when so held. Formed adjacent one end of the frame is an aperture 21 divided by the slot 6 in two sections 22 and 23. The section 23 is provided with tapering walls against which the correspondingly tapered sides 24

- of a bushing or center-piece 26 is adapted to fit. The bushing 26 is initially inserted in the aperture section 23 through the section 22, and may be held loosely or tightly 5 in the former by means of the externally threaded hollow nut 27 which engages the internal threads 28 of the bushing. Extending through the nut and engaging in the threaded portion 29 of the sleeve is a screw 10 31 carrying at its point a feather 32 which is arranged to engage in a longitudinally extending groove 33 formed in one side of the blade. Connection between the screw and feather is provided by means of the 15 reduced end 34 of the screw, which rotatably fits in a central aperture 36 formed in the feather and countersunk for the reception of the flattened extremity of the screw. The feather is held against rotation 20 with respect to the sleeve but allowed reciprocal movement by being mounted in a slot 37 formed in the sleeve. The opposite sides of the groove 33 of the blade are tapered, and the sides of the feather are 25 tapered correspondingly so that the feather may be tightly wedged in the groove when the screw 31 is fully advanced. Suitably held on the sleeve against rotation therewith, is an indicating member 38, which as here 30 shown is formed with a straight sided segment 39 which is adapted to fit against a similar formed segment 41 formed on the portion of the sleeve which protrudes from the aperture. The indicating member is 35 provided with a pointer 42 which is arranged to cooperate with a graduated segment 43 formed on the frame and being concentric with the sleeve. The indicating member is adapted to rest against the side 40 of the frame, and a washer is preferably interposed between said member and the shoulder 44 of the nut 27 so that the turning of the nut will not effect the indicating member or the sleeve. In order that the 45 movement of the nut will be limited and still allow the sleeve to be properly tightened or loosened, I preferably form a cut out segment 46 at the end of the nut and place a screw 45 in the sleeve for engagement with 50 the ends of said segment. When it is desired to use the device as a bevel protractor, the blade is inserted in the slot so that the feather engages the groove. With the blade then moved to the desired angle (as will be 55 indicated by the position of the pointer on the graduated segment) the nut is turned so as to tightly clamp the sleeve and indicator against the frame. The screw 31 is then turned so as to cause the feather to 60 wedge securely in the groove and thereby hold the blade in rigid position. To release the members the foregoing steps are practically reversed. The device is also particularly adapted for measuring the 65 taper of a shaft. This is done by merely

setting one of the sides of the frame and one of the edges of the blade against the side and end of the shaft. The blade may be then clamped and the device will be set to the correct taper.

The sides 47 and 48 are provided with level glasses 49 and 50 respectively, thereby enabling the device to be used as a level and plumb level.

I claim:

1. In a combination square, a frame having a V-shaped depression formed on one face thereof and extending from one end of the frame to the other, said frame being provided with a slot lying parallel to said depression and extending inwardly from the apex thereof, and a blade adapted to slidably fit in said slot and extend into said depression.

2. In a combination square, a frame having a V-shaped depression formed on one side and extending longitudinally thereof, said frame having a slot running parallel with and communicating with said depression and having one side thereof exactly terminating at the apex of said depression and having the other side terminating intermediate one of the sides of said depression, and a blade adapted to slidably fit in said slot and extend into said depression.

3. In a combination square, a frame having a longitudinally extending V-shaped depression formed on one side thereof, said frame having a slot communicating with said depression and having one side thereof terminating exactly at the apex of said depression and having the other side terminating intermediate one of the sides of said depression, and a blade adapted to slidably fit in said slot and extend into said depression, a longitudinally extending portion of the frame from the apex to the other side of said groove being cut away for the insertion of a scribing tool.

4. In a combination square, a frame having a slot, a blade adapted to slidably fit in said slot and provided with a longitudinal groove having tapered sides, and means adapted to press against said sides whereby said blade will be clamped against said frame.

5. In a combination square, a frame having a slot, a blade adapted to slidably fit in said slot and provided with a groove, a feather adapted to engage in said groove, and a screw connected to said feather whereby the latter may be moved in or out of said groove.

6. In a combination square, a frame having a slot, a blade adapted to slidably fit in said slot and provided with a groove having tapering sides, a beveled feather adapted to engage the sides of said groove and provided with an opening, and a screw having one end fixed to said feather and rotatively held in

said opening whereby said feather may be moved in or out of said groove upon the turning of the screw.

7. In a combination square, a frame having a slot and an aperture having tapering walls, a blade adapted to slidably fit in said slot and provided with a groove, a feather adapted to engage in said groove, a sleeve adapted to fit in said opening provided with correspondingly tapered outer walls and a threaded portion, a threaded nut adapted to engage said threaded portion whereby said sleeve may be drawn tightly in said frame, and a screw extending through said nut and engaging in said sleeve adapted for moving said feather in or out of said groove.

8. In a combination square, a frame having a slot and an aperture having tapering side walls, a blade adapted to slidably fit in said slot and provided with a groove, a sleeve fitting in said aperture having outer walls corresponding to said aperture, said sleeve having an internally threaded portion, a threaded nut adapted to engage said threaded portion whereby said sleeve may be tightly held in the frame, and a screw respectively extending through and engaging said nut and sleeve and rotatably attached to said feather whereby the latter will be moved in or out of said groove upon the rotation of the screw.

9. In a combination square, a frame having a slot and an aperture having tapering sides, a blade adapted to slidably fit in said slot and provided with a groove, an internally threaded sleeve fitting in said aperture and tapered correspondingly, an indicating member held on and movable with said sleeve, a feather movable axially in said sleeve and arranged to engage said groove, a threaded nut arranged to engage said sleeve whereby the latter may be held tightly in the frame, and a screw extending through said nut and sleeve rotatably secured to said feather.

45 10. In a combination square, a frame having a slot and an aperture having tapering sides, a blade adapted to slidably fit in said slot and provided with a groove, a graduated segment on said frame concentrically disposed with respect to and adjacent said aperture, an internally threaded sleeve fitting in and tapered externally similar to

said aperture, an indicating member held on and movable with said sleeve and provided with a pointer cooperating with said segment, a feather arranged to engage in said groove and held in said sleeve for axial movement relative thereto, a threaded nut engaging said sleeve adapted for drawing said sleeve tightly against the sides of said aperture, a screw extending through said nut and sleeve and having a threaded engagement with the latter, said feather having a central aperture in which one end of said screw is rotatably secured, and means for limiting the rotation of said nut.

11. In a combination square, a frame formed of a single integral piece and provided with a slot and an aperture having tapering sides, a blade arranged to fit in said slot and provided with a groove having tapering sides, a V-shaped depressed face on one side of said frame communicating with said slot, a level glass and a plumb level glass on other sides of said frame, a portion of the frame adjacent the apex of said depression being cut away whereby a scribe may be inserted into said depression from the outside of the frame, a feather adapted to engage in said groove provided with beveled sides and a central aperture, an internally threaded sleeve arranged in and having its outer sides tapered similar to said first mentioned aperture, said sleeve being provided with a recess for the reception of said feather, a graduated segment provided on said frame and concentrically disposed with respect to said sleeve, an indicating member held on said sleeve for rotation therewith and provided with a pointer for cooperation with said segment, a hollow externally threaded knurled nut engaging in said sleeve and adapted to clamp the sleeve and indicating member and blade against rotation, a screw extending through said nut and sleeve and having a threaded engagement with the latter, one end of said screw being rotatably secured in the central aperture of the feather, and means for limiting the rotation of said nut.

In testimony whereof, I have hereunto set my hand at Oakland, this 23rd day of May, 1922.

EDUARD H. TEMPERLI.
